UNITED STATES PATENT OFFICE.

DONALD V. EICHIN, OF OLNEY, ILLINOIS.

CIGAR-LIGHTER.

1,296,056.

Specification of Letters Patent.

Patented Mar. 4, 1919.

Application filed October 23, 1916. Serial No. 127,236.

To all whom it may concern:

Be it known that I, DONALD V. EICHIN, a citizen of the United States, residing at Olney, in the county of Richland and State of Illinois, have invented a new and useful Cigar-Lighter, of which the following is a specification.

My invention relates to an electric cigar lighter and it is my purpose to provide a device that will positively light at all times. It is my object to provide a device of a vibrating character adapted to produce a shower of sparks stronger than in the ordinary cigar lighter to insure ignition of the wick. It is one of the objects of my invention to provide a device of relatively simple construction.

I attain these and other objects of my invention by the mechanism illustrated in the accompanying drawings, in which—

Figure 1 is a side elevation of one form of my invention; Fig. 2 is a vertical section of the improved form of my invention; Fig. 3 is a vertical section of a modified form of my invention; Fig. 4 is a diagrammatic view of the electric circuits; Fig. 5 is a top plan of Figs. 1 and 3; Fig. 6 is a vertical section of a further modified form; Fig. 7 is a diagrammatic view of same; and Fig. 8 is a top plan of Fig. 6.

Referring to the accompanying drawings, I provide a suitable portable standard 1, having a housing 2 and an opposite lamp 3, which in turn is provided with a wick 4 extending through partition 5. A flame extinguishing door 6, which may be either slidably or pivotally mounted is connected by a suitable link or arm 7 to fulcrum arm 8, the lower end of which is pivoted at 9 to the standard 1, as illustrated in each of the forms shown. Extending through a suitable opening 10 in standard 1 is a push rod 11 connected to and adapted to operate fulcrum arm 8, which is held to its normal position by spring 12. A suitable insulation block 13 is mounted to housing 2, this block consisting of wood fiber. In the improved form of my invention disclosed in Figs. 1 and 2 I provide a contact bar 14 having a vertical hinge 15, which like the contact bar is of brass, mounted in a suitable insulation vertical member 16. A spring 17 holds members 14 and 15 in their normal upright positions but permits of their tilting as hereafter

described. I provide a cam member 18 attached to housing 2 and positioned to engage 55 against the upwardly curved portion or end 20 of maker bar 19 to elevate same to the position shown in dotted lines in Fig. 2. Maker bar 19 is provided with a downward projection 21 adapted to engage against member 15 momentarily. As a conduit for the electric current from primary wire 39 to contact bar 14 I provide a suitable screw or pin 23 extending through insulation block 13. Positioned over wick 4 I provide suitable 65 electrodes 24 and 25, grounded as illustrated in Fig. 2, member 25 being attached to high tension cable 40.

The electric current from battery B travels through primary wire 39, pin 23, contact bar 70 14 and vertical hinge, proceeding no further until the device is operated. When push rod 11 is pressed inwardly it likewise moves fulcrum arm 8 toward housing 2 and causes maker bar 19 to move toward vertical hinge 75 15. When projection 21 on bar 19 comes into contact with the brass vertical hinge 15 the electric current flows through maker bar 19 to the entire machine, and as one primary wire is grounded upon the machine this completes the circuit back to coil C and battery B. A secondary current passes through high tension cable 40 to electrodes 25 and 24, jumping the gap between those members and igniting the gasoline vapor. The contact of 80 projection 21 and vertical hinge 15 is merely a passing contact because as push button 11 is pressed to its farthest position maker bar 19 is lifted by the contact of its curved end 20 with cam member 18, thus clearing it from vertical hinge 15 and breaking the electric circuit. Spring 17 presses vertical hinge 15 back to its upright position and maker bar 19 and its projection 21 slide over the insulation member 16, making no further electrical connection and flame is smothered 90 when lid 6 is moved back over top of lamp 3.

Referring to the modified form disclosed in Figs. 3, 4 and 5, it will be observed that I provide a maker bar 28 of slightly modified 100 construction having a downward projection 30 of modified form and a downwardly projecting catch 29 at its outward end. I provide a contact point 26 electrically connected with wire 39 and corresponding in function 105 with member 15 of the form of my invention

shown in Figs. 1 and 2. I further provide a contact point 27 positioned in proximity to contact point 26 and adapted to be moved into electrical connection therewith by projection 29 of bar 28, the aforesaid members having a function corresponding with that of projection 21 of bar 19 in the form of my invention illustrated in Figs. 1 and 2. I further provide a cam projection 30 on bar 28, having a function corresponding with that of curved end 20 of bar 19 in the form shown in Figs. 1 and 2; and a member 31 adapted to engage against cam projection 30 of bar 28, thus causing projection 29 to disengage from contact point 27, which is resiliently mounted, and break the electrical connection that has been momentarily made between members 27 and 26. It will be seen that the function of member 31 corresponds with that of member 18 in the form of my invention disclosed in Figs. 1 and 2. 41 is the ground connection with standard 1 for both primary and secondary circuits of the vibrating coil, as illustrated diagrammatically in Fig. 4, this figure 25 of the drawings illustrating also the operation of the form of my invention disclosed in Figs. 1 and 2. Other parts shown in Figs. 3, 4 and 5 have been described in connection with Figs. 1 and 2. I provide a suitable slot 32 in the top of standard 1, in each of the forms of my invention, to permit of movement of fulcrum arm 8.

Referring to Figs. 6, 7 and 8, I provide a suitable spring 35 to hold fulcrum arm 8 to its normal position. This spring corresponds as to the function it performs with spring 12 of the other forms of my invention. I provide a push button 33, arranged to operate fulcrum arm 8, and corresponding in 40 that respect to the function performed by push rod 11. It is mounted in an insulation member 34. Push rod 33 carries a contact member 36, having an insulated portion 37, as illustrated in Figs. 6 and 7. Member 36 45 is positioned to momentarily contact with contact member 38 which is grounded on standard 1, as illustrated. Member 38 is sufficiently resilient to allow member 36 to pass over it when push rod 33 is pressed inward, the insulated portion 37 thereupon breaking the electric circuit between contact members 36 and 38, thus performing a function analogous to that of the cam members and of the other forms of my invention, as 50 hereinbefore described. When the electric circuit is completed by the connection of contact members 36 and 38, a high tension shower spark is caused to jump the gap between the two electrodes 24 and 25, as in 55 the other forms of my invention. This shower of sparks occurs only for an instant as the contacts pass each other while cover 6 is sliding open. The gasoline or alcohol vapor from the wick causes ignition to take 60 place. When push button 33 is released the

cover 7 is automatically moved to its original position closing lamp 3 and extinguishing the flame. Insulation 37 on contact member 36 prevents any spark occurring when push rod 33 is released and returns to its outward position. The spark does not occur while the flame is burning, which insures long life for the battery. Each of the forms of my invention provides for a vibrating jump spark, which lights a flame. C 75 designates a vibrating coil in each of the forms.

What I claim is:

1. In an electric cigar lighter, the combination of a standard, a lamp having a lamp wick and having spaced electrodes disposed to provide a gap in immediate proximity to the lamp wick, lamp cover means operatively connected with a fulcrum arm, a fulcrum arm pivoted to the standard, a push rod member arranged to operate the fulcrum arm, means operatively connected with the fulcrum arm for completing an electric circuit, a primary circuit, a vibrating coil, and a second circuit, whereby the make and break of the primary circuit induces a high potential in the secondary circuit to produce a vibrating jump spark to ignite the lamp wick upon operation of the push rod member, substantially as described. 95

2. In an electric cigar lighter, the combination of an electric circuit, said circuit including normally disconnected contact points, means including a push rod and pivoted fulcrum arm for momentarily completing the circuit, means for interrupting the circuit immediately after its completion, and means to prevent its subsequent completion on release of the pusher rod, and a second circuit, a vibrating coil having its primary and secondary windings connected respectively with said first and second circuits, and electrodes positioned in proximity to lamp wick to produce a vibrating jump spark to insure ignition of the lamp wick when the electric circuits are completed. 100

3. In an electric cigar lighter, the combination of a standard, a lamp having a lamp wick, spaced electrodes in proximity to the wick, a removable cover, a pivoted fulcrum arm operatively connected with the cover, a housing mounted on the standard opposite to the lamp, contact members in said housing, an electric circuit terminating in said contact members, means for operating the fulcrum arm to momentarily engage the contact members to complete the circuit, means for breaking the circuit thereafter and preventing its completion on return of the fulcrum arm, a second circuit, a vibrating coil having its primary and secondary windings connected respectively with said first and second circuits, said second circuit terminating in the aforesaid spaced electrodes arranged to ignite the lamp wick, whereby upon oper- 115 120 125 130 135 140 145 150 155 160 165 170 175 180 185 190 195 198

ation of the fulcrum arm the lamp cover will be removed, the first circuit momentarily made and then broken, and a high potential current induced in the second circuit to produce a vibrating jump spark to ignite the lamp wick, and means for automatically returning the fulcrum arm to its normal po-

sition, substantially as and for the purposes set forth.

DONALD V. EICHIN.
